UNITED STATES PATENT OFFICE.

SAMUEL I. RUSSELL, OF CHICAGO, ILLINOIS.

ELECTRIC SADIRON.

1,370,916.

Specification of Letters Patent. Patented Mar. 8, 1921.

Application filed October 6, 1920. Serial No. 415,042.

To all whom it may concern:

Be it known that I, SAMUEL I. RUSSELL, a citizen of the United States, residing at Chicago, in the county of Cook and State 5 of Illinois, have invented certain new and useful Improvements in Electric Sadirons, of which the following is a specification, reference being had therein to the accompanying drawing.

- 10 This invention has relation to electric sad irons and has for its object the provision of a sad iron of comparatively simple and economical construction, having an electric heating element so arranged as to impart to 15 the base or sole plate of the iron a maximum degree of heat with a minimum expenditure of current and in which the heating element is so constructed that it will develop heat only in that portion which lies within the 20 casing or shell of the iron, thus leaving the terminals of the heating element safely and conveniently cool.

The invention consists in the structural features and combinations hereinafter more 25 particularly described and claimed.

In the accompanying drawings,

Figure 1 is a side view of an electric sad iron embodying my invention.

Fig. 2 is a rear end view of the same.

30 Fig. 3 is a vertical transverse section on the line II of Fig. 1.

Fig. 4 is a plan view of the sole plate or base of the iron.

Fig. 5 is a plan view of the pressure plate 35 which rests on the heating element.

Fig. 6 is a detached view, partly in section, of a part of the heating element.

The structure, as a whole, comprises the sole or base plate 1, the pressure plate, 2, the 40 shell or casing 3, the handle holder 4', handle 4 and heating element 6.

For the purposes of my invention the base or sole plate 1, which is a comparatively heavy cast iron plate, is formed with a continuous serpentine, sinuous or laterally undulating groove or channel 7, of any suitable form, but preferably of the form shown in Fig. 4, produced by the outer fluted flange or wall 8, having lateral extensions 9, and 50 the center partition 10, having lateral extensions 11. The groove sections may however be run lengthwise of the sole plate or in any other way which will provide sufficient space and length for the accommodation of a long heating element, which it is 55 desirable should cover as great an area as

possible, so as to impart heat to all the parts of the sole plate. The heating element, in the form of a length of cord, the specific character of which will be hereinafter 60 described, is laid in the groove 7 so that its ends may be carried out at the rear end of the iron, and this heating element is of such a diameter as to closely fill the groove 7.

The sole plate 1 is cast with a marginal 65 flange 12 to embrace the walls of the shell or casing 3, the latter being a pressed steel hollow body of the usual shape, having holes at 1' 1" for the passage of the ends of the heating element.

The pressure plate 2 is a metal casting having the same form in marginal outline as the sole plate, but smaller than the latter, so as to lie within the shell 3 while resting on the flanges forming the groove and is cast 75 with a central hollow boss 12 of such length that its upper end is in contact with the under surface of the shell 3 when the parts of the iron are fitted together as shown in Fig. 3 and so that when the shell is forced 80 down the pressure plate will press upon the top of the heating element and tend to squeeze the latter sidewise so as to bring it into close contact with the metal of the sole plate.

85 The sole plate 1 is cast with a central pillar or post 13, rising from the upper surface of the sole plate and having in its upper end a screw threaded socket 14, for the reception of the threaded shank of a headed screw 15, which is inserted through a hole in the top of the shell and is the means for holding all the parts of the iron together.

The post or pillar 13 terminates a short distance below the upper end of the boss 90 12, so as to leave space for the downward adjustment or pressure movement of the shell and pressure plate.

100 The handle 4, of wood or other suitable non conducting material is supported by a U shaped metal strip 4', and is connected to the shell by the screw 15, the plate or strip 4' being formed with indentations 18, 18, to receive corresponding studs 19, 19, formed on the upper surface of the shell 3, by suitably indenting the under surface. These studs and indentations serve to hold the handle supporting strip 4' in place and prevent its turning on the iron.

105 The pressure plate 2 is formed with a 110 notch 20 at its rear edge for the passage of the ends of the heating element, one of the

ends being run through the hole, 1', at the back of the shell, and the other passed through a hole 1'' in the shell back of the handle strip. The hole 1' is provided with 5 an insulating fiber washer or bushing 21, secured by screws to the shell.

The heating element 6 is in the form of a length of cord, and comprises a central core 5' of asbestos, on which is spirally wound a 10 wire 5" of suitable resistance for heating purposes, such as tungsten. This wire is tightly wound upon the core so as to sink into the asbestos, and upon the wire covered core is wound an asbestos yarn 6' which 15 forms an insulator of heat conducting properties. Near the ends of the heating element, the wire covered core has, for a short distance, wound upon it and in contact with the resistance wire, a copper or other good 20 conducting wire 22, which for its length short circuits the current so as to prevent the ends of the heating element becoming heated and imparting heat to the shell and

other parts of the iron near the projecting terminals. The only part of the heating 25 element which is effective is that part under pressure of the pressure plate hence there is no loss of heat or the development of heat where it would be unsafe, inconvenient, or otherwise undesirable. 30

I claim.

The electric sad iron herein described, comprising a sole plate having a sinuous or serpentine groove in its upper surface, a heating element laid in said groove and consisting of a non-conducting core, a winding of resistant wire, and an insulating shield, a pressure plate adapted to rest upon and compress said heating element, a shell or casing provided with a handle and means 35 for connecting the sole plate, pressure plate, handle and casing together, and for allowing said pressure plate to be adjusted 40 vertically.

SAMUEL I. RUSSELL.
